UNITED STATES PATENT OFFICE.

MATT F. SWANSON, OF STREATOR, ILLINOIS.

FIRE-BOX FOR KILNS.

1,246,179.

Specification of Letters Patent.

Patented Nov. 13, 1917.

Application filed April 4, 1916. Serial No. 88,879.

To all whom it may concern:

Be it known that I, MATT F. SWANSON, a citizen of the United States, and a resident of Streator, in the county of La Salle 5 and State of Illinois, have invented certain new and useful Improvements in Fire-Boxes for Kilns, of which the following is a specification, reference being had to the accompanying drawings.

10 This invention relates to certain novel improvements in kilns, and the primary object of my invention is to provide a kiln of the down draft type with a simply constructed fire box arranged to entirely consume the 15 smoke and other products of combustion.

Another object is to provide a kiln having a fire box so constructed that the grate may be cleaned without the loss of any fuel and without extinguishing the fire.

20 And finally the object of my invention is to provide a kiln with a fire box assuring economy of fuel in that each fuel atom is converted into a heat unit while the furnace can be economically fired.

25 With these and other objects in view, the present invention consists in the combination and arrangement of parts as will be herein-after more fully described, and finally pointed out in the appended claims, it being further understood that changes in the specific structure shown and described, may be made within the scope of the claims without departing from the spirit of the invention.

In the accompanying drawings forming a 35 part of this specification, and in which like numerals of reference indicate similar parts in the several views:—

Figure 1, shows a sectional view on a horizontal plane of a fire box constructed according to my invention, a portion of the 40 kiln being shown.

Fig. 2, is a vertical sectional view of a fire box constructed according to my invention.

In my present invention, I provide a fire 45 box comprising a forwardly located imperforate coking table, an intermediately positioned grate, and a rear dead table, providing a fuel and labor saving fire box. The fire box is especially adapted to be used in burning bituminous coal which in the use 50 of my invention, is placed on the coking table from which the smoke, gases, and other products of combustion pass over the fire upon the intermediately positioned grate. 55 This insures the fuel upon the coking table being thoroughly coked. In cleaning the

grates, which is often necessary, the fire upon the grates is pushed on the imperforate dead table which allows the grate being cleaned without the waste of any fuel. 60 After the grates are cleaned, the fire from the dead table is drawn upon the grates and renewed by shoving the coke from the coking table with the fire over the grates, providing a free burning fire without in any way, 65 having lowered the temperature of the kiln.

In the accompanying drawings, 1 designates the front wall, 2, 2, two side walls, 3, the top wall, and 4, the fire bag of the kiln. As shown, in Fig. 1, the furnace is 70 divided into three sections, the forward section including the coking table, the intermediate section, the grates, and the rear section, the dead table, which extends back to the fire box. 75

Extending from the side walls 2, 2 is the kiln wall 6, while extending from the kiln wall 6, and the fire bag 4, is the base 5.

The fire box proper includes a front arch 7, and a rear arch 8. The front arch 7 80 has a greater radius than the rear arch 8. The line α designates the lower edge of the front arch 7, while the line ν designates the lower edge of the rear arch 8. This insures the heat being crowded in leaving the fire 85 box, which enters and escapes in opposite directions through the side flues F.

Secured adjacent to the forward edge of the side walls 2, 2 are the brace bars 10 while secured near the inner end of the side 90 walls 2, 2 are the I-beams 11, these beams 11 and brace bars 10 being connected by means of the stay bolts 12, this construction being clearly shown in Fig. 1.

Located within the front wall 1, is the 95 upper fuel opening a and the lower ash pit opening b . The opening a is closed by means of a sliding fuel door 13 while the ash pit opening b is closed by means of a sliding door 14, this door 14 working at its 100 lower edge within a groove 17, its upper edge being held behind the guide flange 15, which also gives support to the lower edge of the upper fuel door 13, the upper edge of which is guided by the upper flange 16, 105 as shown in Fig. 2.

Positioned in alinement with the top of the base 5 is the base plate 18 having the upstanding flange c and the forward stub flange e . Held upon this base plate 18 and 110 between the flanges c and e is the imperforate coking table T.

This coking table T extends from one side wall 2, to the other, as shown in Fig. 1. Resting upon the extension of the base plate 18 is the grate G, of any approved construction, which has its rear end resting upon the table base 20 upon the top of the base 5. Held upon this table base 20 is the dead table D, made of any non-combustible material as fire brick or the like, as is the 10 coking table T.

As shown in Fig. 2, the forward arch 7 extends backward to a point approximately midlength of the grate G while the rear or similar arch 8 extends from a point approximately central to the grate and ends at a point approximately central to the dead table D.

As shown in Fig. 1, the width of the coking table T is greater than the width of 20 the grates G while the dead table D has the lateral wings or ends d, these wings d extending laterally between the fire bag 4 and the kiln wall 6.

In the use of a fire box constructed according to my invention, there is no waste 25 of fuel or heat and the furnace further can be economically fired.

In cleaning the grates, the partly consumed fuel is placed upon the dead table 30 in the manner explained.

The products of combustion further, escaping from the coking table pass through and over the flames of the fire upon the grates insuring a perfect combustion.

35 As the coking table is imperforate, there is no loss of fuel during the coking operation. The fire box further is simple and inexpensive in construction, and both durable and efficient in operation, and the grates 40 which are the parts apt to become clogged, may be cleaned with ease, accuracy, and despatch.

Having thus described my said invention, what I claim as new and desire to secure by 45 U. S. Letters Patent is:—

1. A smoke consuming fire box for kilns comprising a front wall, two side walls, and a top, having an arched ceiling divided into a forward and a rear portion, said front

wall having a fuel opening and an ash pit 50 opening, a fire bag being located in spaced relation to the inner ends of said side walls and reaching to said top to provide laterally extending side flues, a pier extending from said fire bag inwardly from one side wall to the other, a portion of said pier also extending outward between said side walls and fire bag, a table base upon said pier, and the lateral extensions thereof, a dead table upon said table base, the width 60 of said dead table being less than the width of said table base to provide a supporting edge, a base plate located within the forward portion of said fire box having a rearwardly extending supporting edge, a coking 65 table upon said base plate, and a grate supported upon said edges, the rear arched ceiling of said furnace being of a radius less than that of said forward ceiling portion to crowd the heat as it escapes out of the 70 fire box.

2: A smoke consuming fire box for kilns comprising a front wall, a top, two side walls, and a fire bag arranged in spaced relation to the ends of said side walls and 75 reaching to said top, the ceiling of said top being arched and divided into two portions, a forward and a rear arch, a pier extending from said fire bag inwardly from one side wall to the other and having ends located 80 between the ends of said side walls and said fire bag, a dead table upon said pier, a coking table located within the forward portion of said furnace, and a grate which is intermediate of said coking table and said 85 dead table the upper surfaces of said tables and grate being in a common plane, said rear arched ceiling portion being of a radius less than that of the forward portion to crowd the heat as it escapes from the fire 90 box between said wall ends and fire bag.

In testimony whereof I affix my signature, in the presence of two witnesses.

MATT F. SWANSON.
